B. WEXLER,
ELEVATOR DOOR,
APPLICATION FILED APR. 28, 1917.

Patented Jan. 17, 1922.

Fig. 1 Benjamin Wexler Inventor

By his Attorney
Frank J. Neutrom

UNITED STATES PATENT OFFICE.

BENJAMIN WEXLER, OF BROOKLYN, NEW YORK, ASSIGNOR TO THE PEELLE COMPANY, OF BROOKLYN, NEW YORK, A CORPORATION OF NEW YORK.

ELEVATOR DOOR.

1,403,995.

Specification of Letters Patent. Patented Jan. 17, 1922.

Application filed April 28, 1917. Serial No. 165,097.

To all whom it may concern:

Be it known that I, BENJAMIN WEXLER, a citizen of the United States, residing at the borough of Brooklyn, city of New York, county of Kings, and State of New York, have invented certain new and useful Improvements in Elevator Doors, of which the following is a specification, reference being had therein to the accompanying drawings, 10 which form a part thereof.

My invention relates to elevator doors and more particularly to that type of door which is known as a "truckable" door.

Heretofore in doors of this type, the top 15 frame of a door has been provided with a laterally extending bar projecting beyond the sides of the door and adapted to engage stops carried by either the tracks, or guides, for a door, or by the sill of the elevator 20 shaft. Ordinarily a two section counterbalanced door structure is used, although, under some conditions, a single panel door is employed. With either door structure there is a tendency of the sudden stopping 25 of the door at the sill to cause the movement of the door sections, when a counterbalanced door is used, or of the counterweight, when a single panel door is used, to develop slack in the suspension means for the door, 30 with resultant likelihood of a movement of the lower door section, or of the entire door, when the other door section, or counterweight, takes up this slack. The greater the 35 length of the suspending means, the greater is the tendency for the creation of this slack, and to minimize this condition it is more or less a general practice to form part of this suspending means of an eye bar.

In elevator door structures made in accordance with my invention, I dispense 40 with the stops adjacent the sill, and utilize a portion of the suspension means for the door, to accurately position the door with the truck bar on substantially the level of 45 the sill of the door opening, with the two-fold result of minimizing the likelihood of the development of slack in this suspension means, and preventing side swaying of the suspension means, as a consequence thereof. 50 I also so construct and arrange the suspension stop as to guide the suspension means for the door and limit the movement of the

portion thereof adjacent the truck bar to a substantially, vertical movement.

In a door made in accordance with my invention, the truck bar by reason of the independent adjustability of the connection between the door and the suspension means, may be trued up more readily than is possible when using fixed stops adjacent the 60 sill.

By reason of the position and construction of the stops they may be quickly assembled in the door structure and are so positioned as to transmit the stresses to the tracks or 65 rails at a point and in a manner to lend the maximum strength to the entire door structure.

The invention consists primarily in an elevator door embodying therein a vertically movable door section, means adapted to counterweight said section, flexible suspension means connecting the opposite sides of said door section and said counterweight means, a truck bar carried by said door 70 adapted to substantially span the gap between the sill of the door opening and the elevator car, stops mounted in the elevator shaft intermediate the sill and lintel of the door opening and having an opening therethrough respectively through which the suspension means for said door passes, and contacts carried by said suspension means 75 adapted to engage said stops respectively, whereby said door section will be held by 80 said suspension means with said truck bar on substantially the level of the sill of the door; and in such other novel features of construction and combination of parts as are hereinafter set forth and described and 85 more particularly pointed out in the claims hereto appended.

Referring to the drawings,

Fig. 1 is an elevation of an elevator door embodying my invention;

Fig. 2 is a plan view of one of the stops and the contact co-operating therewith carried by the suspension means;

Fig. 3 is a rear elevation of a portion of one of the tracks or guides, the suspension 100 means for the door section and of one of said stops; and

Fig. 4 is a side elevation of that portion of the invention shown in Fig. 3.

Like letters refer to like parts throughout the several views.

In the embodiment of my invention shown in the drawings, I have indicated at *a* a portion of an elevator shaft having therein a plurality of door openings *b* having the usual lintel *c* and sill *d*.

Upon opposite sides of the door opening *b* are arranged tracks or guides for the door closing the opening, each consisting of a vertically extending angle bar *e*, one flange of which is attached to the wall *a*, and the other flange of which has mounted thereon a second angle bar *f*, one flange of which 15 extends toward the door opening.

Adapted to close the door opening *b* is a vertically slideable door structure which in the form of the invention shown, consists of two counterbalanced door sections *g*—*h* 20 having opposite movement in the same vertical plane. The section *g* has guide shoes *g'* straddling the inwardly directed flanges of the bars *f*, and the section *h* has similar shoes *h'*. The type of door shown in the 25 drawings is known as a "counter-balanced" door, the section *g*—*h* being of substantially the same weight, and being connected at each side thereof by flexible suspension means passing over the pulleys *i*—*i'* adjacent the 30 door lintel. This suspension means in the form of the invention shown, is of a well known type, consisting of eye bars *j* connected with the lower door section, and chains *j'* connected with said eye bars, 35 passed over the pulleys *i*—*i'* and connected with the lower portion of the upper door section *g*.

The door sections *g*—*h* are provided with any desired form of lock *k*.

40 The upper frame of the door section *h* is provided with a transverse top bar *m* extending beyond the sides of the door, the eye bars *j* being secured adjacent the opposite ends of said bar. This bar in addition to 45 serving as a means for attachment of the suspension means for the door structure, also imparts a desired rigidity to the top of the lower door section and acts as a support for a plate *n* of a width sufficient to substantially 50 span the gap between the sill *d* and an elevator car and known in the art as a "truck" bar. This construction is not essential to my present invention, however, and is merely a matter of design.

55 Heretofore, it has been a common practice to provide stops within the elevator shaft adjacent the sill *d* adapted to be engaged by the protruding ends of the top bar *m*, when the door is opened to the full extent, so as to accurately position the truck bar, with relation to the plane of the door sill. With this construction, if the door be opened violently, the engagement of the 60 said bar and stops, and the momentum acquired by the upper door section, or by a

counterweight where a single door panel was used, would result in the creation of considerable slack in the chains *j'* allowing the rods *j* to swing out of the vertical plane. The effect of the slack was to permit a return 70 movement of the upper door section with a sufficient velocity to not only subject the suspension means to violent stresses tending to strains or break same, but to raise the lower door section slightly so that the passage of a loaded vehicle over the truck bar, would subject the stops to severe blows which would tend to disarrange the entire door structure. 75

To avoid this condition, I so construct the 80 door and its suspension and guiding means, that the stops acting directly upon the lower door section will be dispensed with, and the positioning of this door section will be effected through the suspension means itself. 85 At the same time the stops will prevent side swaying of the eye-bar, and thus reduce the likelihood of the creation of excessive slack in the suspension means, or the development of stresses which will tend to snap the said 90 suspension means, or raise the lower door section. Furthermore, by relying on the suspension means to sustain a load upon the truck bar, any movement of the lower door due to a possible springing of the top bar 95 thereof, will have no effect upon the other door section or a counterweight.

In securing these results, I mount upon each track or guide, a bracket *o* at a point substantially midway between the sill and 100 lintel of the door opening, which bracket has therethrough a vertically extending guide opening *o'* through which the suspension means passes. About said opening *o'* a horizontal seat is formed upon the bracket, 105 which seat is adapted to engage a contact member *p* carried by said suspension means. In the form of the invention shown, this member *p* comprises an enlarged head upon the eye bar *j* which is slotted, as shown in 110 Fig. 4, to afford strong and convenient means whereby the chains *j'* may be connected thereto.

The bracket *o* is bifurcated as shown in 115 Figs. 2 and 4, the arms *o*² and *o*³ thereof, being slipped over the bar *j* and attached to the bar *e* in assembling the door. In this manner, the accurate positioning of the two brackets used upon each door is facilitated, and side swaying of the bar *j* is prevented, 120 in all directions except toward the guide *e*. The quantity of this movement is so limited, however, that it is not objectionable.

The lower end of each eye bar *j* is screw 125 threaded, as shown in Fig. 1, this screw threaded end being passed through an opening in the top bar *m* and adjustably secured in relation thereto by means of the nuts *q*—*q'*. By this construction the truck bar may be leveled at any time. Other well 130

known means of attaching the suspension means to the top bar, may be employed, however. The operation of the herein described device is substantially as follows:—

- 5 After the tracks or guides $e-f$ have been installed in the elevator shaft b and the doors $g-h$ have been mounted thereon and connected by the suspension means $j-j'$, the truck bar n of the lower door section is
 10 brought upon the plane of the sill d by means of the nuts $q-q'$, the upper door section g being accurately positioned in relation to the lintel c . When the parts are in this position a bracket o is located upon
 15 one flange of each of the bars e in the proper relation to the contact members p . The bracket o is then slipped with the arms o^2-o^3 thereof on opposite sides of the eye bar j and secured by bolts, rivets or in any
 20 desired manner to the bar e . In this manner, accurate positioning of the truck bar each time the door is opened, is assured.

In use, when the lock k is released and the section g is moved upwardly, the door
 25 section h will descend, the eye bars j being held in substantially vertical position by the bracket o during this movement. In the event that the section g is moved up too violently, some slack may be created
 30 in the flexible section j' of the suspension means, but under no circumstances can the eye bar j move away from the bar e . In this manner, the engagement of the contact members p with the seat upon each bracket
 35 o , will arrest the downward movement of the lower section h and hold the door suspended from said bracket.

By using a rigid section of the suspension means for sustaining the load of the lower
 40 door section a loss of accuracy in the position of this section by the stretching of the suspension means is avoided. In this respect, the use of eye bars is preferable to the use of the continuous chain extending
 45 from door section to door section. By preventing side swaying of the eye bar section, the snapping of the suspension means in this slack is prevented.

By using a bracket having an extended base, as shown, and by mounting this bracket intermediate the sill and lintel, likelihood of displacement thereof is reduced to a minimum. Furthermore, the construction described, limits the application of stresses
 55 upon this bracket to directly vertical stresses.

It is not my intention to limit the invention to the precise details of construction shown in the accompanying drawings, it being apparent that such may be varied without departing from the spirit and scope of the invention.

Having described the invention what I claim as new and desire to have protected by Letters Patent is:—

- 65 1. An elevator door embodying therein a

vertically movable door section, means adapted to counterweight said section, flexible suspension means connected with the opposite sides of said door section and said counterweight, a traction surface at the top 70 of said door section adapted to substantially span the gap between the sill of the door opening and the elevator car, stops mounted within the elevator shaft at opposite edges of, and intermediate the sill and lintel of 75 the door opening, said stops each having an opening extending therethrough, the suspension means for said door passing through said openings respectively, and contacts carried by said suspension means and adapted 80 to engage said stops respectively whereby said door section will be held by said suspension means with said traction surface on substantially the plane of the door sill.

2. An elevator door embodying therein 85 vertically extending tracks or guides upon opposite sides of the door opening, a vertically movable door section slidably mounted upon said tracks or guides, means adapted to counterweight said section, flexible suspension means connecting opposite sides of said door section and said counterweight, a traction surface at the top of said door section adapted to substantially span the gap between the sill of the door opening and the 90 elevator car, stops mounted upon said tracks or guides intermediate the sill and lintel of the door opening, said stops each having an opening therethrough, the suspension means for said door section passing through said 95 openings respectively, and contacts carried by said suspension means and adapted to engage said stops respectively whereby said door section will be held by said suspension means with said traction surface on substantially the plane of the door sill.

3. An elevator door embodying therein a plurality of door sections vertically movable in opposite directions in the same plane, pulleys at each side of said door opening adjacent the lintel thereof, flexible suspension means passing over said pulleys and connecting the opposite sides of said door sections with each other, a traction surface at the top of the lower door section adapted 110 to substantially span the gap between the sill of the door opening and the elevator car, stops mounted within the elevator shaft at opposite edges of, and intermediate the sill and lintel of the door opening, said stops each having an opening extending there- 115 through, the suspension means for said lower door section passing through said openings respectively, and contacts carried by said suspension means and adapted to engage 120 said stops respectively whereby said door section will be held by said suspension means with said traction surface on substantially the plane of the door sill.

4. An elevator door embodying therein 130

- vertically extending tracks or guides upon opposite sides of the door opening, a plurality of door sections slidably mounted upon said tracks or guides and adapted to have movement in opposite directions in the same plane, pulleys at each side of said door opening adjacent the lintel thereof, flexible suspension means passing over said pulleys and connecting the opposite sides of said sections with each other, a traction surface at the top of the lower door section adapted to substantially span the gap between the sill of the door opening and the elevator car, stops mounted upon said tracks or guides intermediate the sill and lintel of the door opening, said stops each having an opening therethrough, and the suspension means connecting said door sections passing through said openings respectively, and contacts carried by said suspension means and adapted to engage said stops respectively whereby said lower door section will be held by said suspension means with said traction surface on substantially the plane of the door sill.
5. An elevator door embodying therein vertically extending tracks or guides upon opposite sides of the door opening, a plurality of door sections slidably mounted upon said tracks or guides and vertically movable in opposite directions in the same plane, pulleys at each side of the door section adjacent the lintel thereof a traction surface at the top of the lower door section adapted to substantially span the gap between the sill of the door opening and the elevator car, brackets mounted upon said tracks or guides intermediate the sill and lintel of the door opening, said brackets each having a horizontally extending seat having an opening therethrough, eye bars connected with the opposite sides of the lower door section passing through the openings of said brackets respectively, an enlarged head upon said eye bar adapted to engage the seat upon said brackets respectively when said traction surface is on substantially the plane of the door sill, and a flexible connection between the enlarged head of said bars and the other door section, said flexible connections passing over said pulleys, said brackets being bifurcated whereby they may be adjusted with relation to said eye bars with said tracks or guides after said suspension means have been connected with said door section.
6. An elevator door embodying therein vertically extending tracks or guides upon opposite sides of the door opening, a plurality of door sections slidably mounted upon said tracks or guides and vertically movable in opposite directions in the same plane, pulleys at each side of the door section adjacent the lintel thereof a traction surface at the top of the lower door section adapted to substantially span the gap between the sill of the door opening and the elevator car, brackets mounted upon said tracks or guides intermediate the sill and lintel of the door opening, said brackets each having a horizontally extending seat having an opening therethrough, eye bars connected with the opposite sides of the lower door section passing through the openings of said brackets respectively, an enlarged head upon said eye bar adapted to engage the seat upon said brackets respectively when said traction surface is on substantially the plane of the door sill, a flexible connection between the enlarged head of each of said bars and the other door section, said flexible connections passing over said pulleys, said brackets being bifurcated whereby they may be adjusted with relation to said eye bars upon said tracks or guides after said suspension means have been connected with said door sections, and means whereby the connections between said eye bars respectively and said lower door section may be adjusted to vary the length of said connections between the door sections to accurately position the lower section with relation to the lower sill.
- In witness whereof, I hereunto have affixed my signature in the presence of two subscribing witnesses, this second day of April 1917.
